ADJUSTABLE BLOCK FOR FROGS.

1,151,097.

Specification of Letters Patent. Patented Aug. 24, 1915.

Application filed April 22, 1915. Serial No. 23,008.

To all whom it may concern:

Be it known that I, BENEDICT T. GIBBS, Jr., a citizen of the United States, residing at Chicago Heights, in the county of Cook and State of Illinois, have invented a certain new and useful Improvement in Adjustable Blocks for Frogs, of which the following is a specification.

This invention relates to railroad tracks and to the use therein in connection with switch tracks of hard metal frogs well known in the art having extending from one end two separated diverging projections between which two ordinary track rails are to be placed at an angle to each other and secured to the frog. It is common practice to place between such two diverging rails a wedge block performing the double function of forcing the rails into good contact with the frog projection and filling the apex of the angular space between the rails while said space is sufficiently narrow so that the foot of a workman or trespasser could get caught between the rail end portions. When a one-piece solid metal spacing block is used provided with transverse holes for bolts securing the frog rails and spacing blocks together, it is impossible within the financial limits imposed on the art to make the parts sufficiently accurate so that they will go together properly in the first instance and so that they will remain in adjustment under various conditions of wear of the parts.

The object of this invention is to provide a two-part wedge device for filling the space between the rail ends, said wedge parts being adjustable with reference to each other and one of them being adjustable with reference to the bolts for securing all the parts in place so that in installing the device the parts may all be fitted together in proper relationship without undue expense and that later adjustments may be made to compensate for wear as it takes place.

Another object is to make the device adjustable without removing it from position between the rails.

The invention consists in a device capable of carrying out the foregoing objects, which can be easily and conveniently made and installed, which is satisfactory in use and not readily liable to get out of order.

The invention further consists in the con-

struction and features hereinafter more fully described and claimed.

Referring to the drawings, in which similar numerals indicate the same parts throughout the several views, Figure 1 is a plan view of an entire railroad frog having the rails which are attached at the left hand end thereof equipped with the device of this invention. Fig. 2 is an enlarged plan view partially in section of the wedge or spacing device of this invention removed from the frog and the adjacent rails. Fig. 3 is an enlarged plan view of the left hand end of Fig. 1 showing the device of this invention applied to the frog. Fig. 4 is a transverse sectional end view taken on the line 4—4 of Fig. 1. Figs. 5 and 6 are perspective views of the two parts of the wedge separated from each other. Fig. 7 is an end view of the wedge device in assembled position.

A hard metal frog 10, shown in Fig. 1, is only one of various frogs of this general type which might be shown to illustrate the application of this invention in connection with its two rearwardly extending, angularly placed, projections 12 and 14, shown enlarged in Fig. 3, between which the rails 16 and 18 are rigidly secured in place.

The spacer block or wedge of this invention comprises the two parts 20 and 20^a, clearly shown in perspective in Figs. 5 and 6, and is, as clearly shown in Fig. 3, made with its side edges 22 and 24 of the same angularity with reference to each other as the angle of the rail 16—18 when they are in proper position within the frog. This wedge is made of such a height, as clearly appears in Fig. 4, that it fills all the space between the ends of the rails 16—18 except that the upper surface 26 is recessed to permit the passage of the wheel flanges on the wheels which travel along the tracks 16 or 18.

The parts 20 and 20^a of the wedge are separated one from the other along the preferably substantially straight line 28 made preferably substantially parallel to one of the angular faces 22 or 24 of the wedge, in the particular case here illustrated 24. One of the wedge parts is provided on its face 28, just referred to, with a projecting lug 30 adapted to lie and travel in a correspondingly formed notch or recess 32 in the other

part. In the case here illustrated, this recess 32 is in part 20^a and the lug or rib 30 is on part 20 but, obviously, these locations may be reversed without departing from this invention. At the end of the wedge, means is provided for detachably securing the two parts 20 and 20^a together in different selected positions with reference to each other. In the case here illustrated, this means consists in providing a pin or cotter pin 34 adapted to pass through one particular hole 36 in one of the wedge parts and a selected one of several differently placed holes 38 in an enlarged portion of the lug 30, heretofore referred to. In the particular case here illustrated, the holes 38 are staggered with reference to each other along adjacent parallel lines in order to make the effective distance between successive holes shorter than as though they were placed on one straight line parallel to face 28. In view of this disposition of the holes 38, the hole 36 is made in the form of an elongated slot extending transversely of part 20^a, as shown.

The spacing wedge block, just referred to, is like many prior devices of this character secured in place by bolts 40 passing through the block, adjacent rails 16 and 18 and the frog projections 12 and 14. These bolts 40 pass through ordinary round holes 42 in part 20^a made simply large enough to let the bolts go through in the ordinary manner, while in the case of part 20 of the wedge, holes 44 are provided elongated in the direction of the block, as clearly appears in the figures, so that within proper limits the portion 20 of the block may move lengthwise of portion 20^a without being stopped by the bolts 40.

The result of the construction just described is that when the wedge-block is put in place between the rails, as illustrated in the figures, and it is found any adjustment is necessary in order to make it fit right and do its work, it is only necessary for the operator to remove the cotter pin 34 and move part 20 of the wedge to the position which will make the entire wedge fit properly and then insert the cotter pin in the nearest adjacent hole 38, heretofore described. This adjustment may be made in either direction and it may, of course, be made and, in fact, should be made once at the time all the parts are first assembled. When wear takes place the cotter pin is removed and the portion 20 is, after first loosening the bolts 40, driven up and the cotter pin replaced in a new hole 38, all this without removing the block from its position in the track.

Having thus described my invention, what I claim as new and desire to secure by Letters Patent, is: —

1. In combination with two angularly placed rails and transverse bolts for secur-

ing them together; a wedge shaped spacing and filler block between said rails, pierced by said bolts, and made in two parts permitting one of said parts to slide while in place between the rails with reference to the other in the direction of the length of the rail, the holes, through the movable block part, through which said bolts pass, being elongated in the direction of the length of the rails to permit said movement, and means for detachably securing said wedge block parts together in selected different positions with reference to each other.

2. In combination with two angularly placed rails and transverse bolts for securing them together; a wedge shaped spacing and filler block between said rails, pierced by said bolts, and made in two parts permitting one of said parts to slide while in place between the rails with reference to the other in the direction of the length of the rail, the holes, through the movable block part, through which said bolts pass, being elongated in the direction of the length of the rails to permit said movement, while the holes in the other block part are merely of normal size to receive said bolts, and means for detachably securing said wedge block parts together in selected different positions with reference to each other.

3. In combination with a railway track frog having extending from one end two separate diverging projections, track rails angular to each other placed between said frog projections, and bolts passing through said frog projections and rails for securing them together; a wedge shaped spacing and filler block for forcing said rails into contact with said frog projections, between said rails, pierced by said bolts, and made in two parts, permitting one of said parts to slide while in place between the rails with reference to the other in the direction of the length of the rails, the holes through said movable block part through which said bolts pass being elongated in the direction of the length of the rails to permit said movement, and means for detachably securing said wedge block parts together in selected different positions with reference to each other.

4. In combination with a railway track frog having extending from one end two separate diverging projections, track rails angular to each other placed between said frog projections, and bolts passing through said frog projections and rails for securing them together; a wedge shaped spacing and filler block for forcing said rails into contact with said frog projections, between said rails, pierced by said bolts, and made in two parts, permitting one of said parts to slide while in place between the rails with reference to the other in the direction of the length of the rails, the holes through said

- movable block part, through which said bolts pass being elongated in the direction of the length of the rails to permit said movement while the holes in the frog projections, the rails and the other block part through which the bolts pass are merely of normal size to receive said bolts, and means for detachably securing said wedge block parts together in selected different positions with reference to each other.
- 5 5. In combination with two angularly placed rails and transverse bolts for securing them together; a wedge shaped spacing and filler block between said rails, pierced by said bolts, and made in two parts permitting one of said parts to move with reference to the other in the direction of the length of the rail, the holes, through the movable block part, through which said bolts pass, being elongated in the direction of the length of the rails to permit said movement, 40 while the holes in the other block part are merely of normal size to receive said bolts, a guiding flange on one of said block parts along the surface of separation between them lying in a corresponding recess in the 45 other part, and means acting through said flange and the part in which it lies for selectively securing the block parts in different positions with reference to each other.
- 10 6. In combination with two angularly placed rails and transverse bolts for securing them together; a wedge shaped spacing and filler block between said rails, pierced by said bolts, and made in two parts permitting one of said parts to move with reference to the other in the direction of the length of the rail, the holes, through the movable block part, through which said bolts pass, being elongated in the direction of the length of the rails to permit said movement, 40 while the holes in the other block part are merely of normal size to receive said bolts, a guiding flange on one of said block parts along the surface of separation between them lying in a corresponding recess in the 45 other part, and means acting through said flange and the part in which it lies for selectively securing the block parts in different positions with reference to each other.
- 15 7. In a device of the class described, two 50 members contacting each other in a straight line movable with reference to each other along said line, a flange or rib on one of said members entering a recess in the other member to prevent lateral displacement of said 55 members with reference to each other while permitting said longitudinal movement, and means cooperating with said flange and the one of said parts in which it moves for selectively adjustably securing said part in 60 different positions with reference to each other.
- 20 8. In witness whereof, I have hereunto subscribed my name in the presence of two witnesses.
- 25 9. BENEDICT T. GIBBS, Jr.
